UNITED STATES PATENT OFFICE.

CARL S. WEYANDT, OF PITTSBURGH, PENNSYLVANIA, ASSIGNOR TO CENTRAL ELECTRIC TOOL COMPANY, OF PITTSBURGH, PENNSYLVANIA, A CORPORATION OF PENNSYLVANIA.

ELECTRIC TOOL.

Application filed July 26, 1922, Serial No. 577,720. Renewed June 8, 1926.

My invention relates to electric tools of the hammer class where an electromagnetically operated armature is caused to vibrate or reciprocate and operate a hammer, riveter, 5 drill, chisel, or the like.

It is the object of the present invention to provide a tool of the class mentioned which is compact, readily assembled and taken apart, well sealed against the admission of 10 moisture to the windings and other interior parts, comparatively simple in construction, and reliable and efficient in use.

Referring to the accompanying drawing, Fig. 1 is a central longitudinal section of 15 my improved tool in its preferred form, and Fig. 2, a cross-section on the line II—II of Fig. 1.

On the drawings, 2 designates a non-magnetic cylinder or barrel in which the magnetic core, armature, or striking element 1 is reciprocable. The barrel has at one end the external threads 4 and at the other end the internal threads 5, and is surrounded by two electromagnets 6 and 7 which have the 20 respective windings 37 and 38 and whose magnetic circuits are separated by the fibre washer 8. The magnets have their magnetic circuits composed partly of the steel casing 9 and partly of L-shaped laminated 25 steel field members 10 arranged radially around the barrel. Each member 10 has a radial arm 11 lying against an end of a winding and an arm 12 lying parallel with the barrel between the latter and a winding. 30 Each magnet has two annular series of field members with the free ends of the arms 12 of one series facing or opposite the corresponding ends of the other series, providing air gaps wholly within the windings. These 35 ends are beveled and have lugs or extensions 13 in slots in the barrel 2. The outer ends of the arms 11 engage the casing 9 of magnetizable material.

14 is a cap screwing on the threads 4 and 40 having the flange 15 which bears against a fibre washer 16 imbedded in the inner wall 17 of the opening 18 in the handle 19. A short fibre ring 20 lies between the cap and the handle and abuts against the washer 16. 45 A fibre washer 21 abuts against the inner end of the handle and the ring 20 surround-

ing the cap, and bears against the inner end of the casing 9. A fibre washer 22 lies between the cap and the casing, and also between the washer 21 and the arms 11 nearest 55 the handle.

The handle end of the barrel contains the reciprocable hollow core-stop 23 having its outer end closed and having the flange 24 working in the enlarged portion 25 of the 60 barrel and limited in its inner movements by the shoulder 26 and in its outer movements by the coiled spring 27 between the closed ends of the cap and core-stop. 28 is a set-screw threaded in the handle and engaging the cap 14 to prevent the accidental 65 loosening of the cap.

29 is a non-magnetic nose piece or cap which engages the outer end of the casing 9, surrounds the outer end of the barrel, and 70 has a flange 30 abutting against the said end of the barrel. A steel tool bushing 31 extends through the cap 29, screws into the threads 5, and has the flange 32 which engages the washer 33 on the end of the cap 29. 75

34 is a tool, such as a riveting tool, or a drill, having the shank 35 slidable in the tool bushing 31, the tool having a shoulder 36 adapted to engage the bushing when the tool is in its innermost position, as shown 80 in Fig. 1. When in this position the end of the shank projects beyond the inner end of the bushing and lies about opposite the outer circle of lugs 13, preferably about as shown in Fig. 1. Of course, good results 85 may be had if the end of the tool is not placed precisely as shown.

The end surfaces of the tool shank 35 and of the core stop 23 should be so disposed, relative to the air gaps between the lugs or tenons 13, that one end of the core 1 will project into one air gap when the other end of the core is at its extreme operating position adjacent the other air gap. Thus, when the core engages the tool shank, its rear end surface should be adjacent the air gap of rear solenoid 6. When the core engages the core stop, its front end surface should be adjacent the front air gap of solenoid 7. The core 1 in its forward and backward movements closes each air gap or reduces each air gap to minimum length, and continues be-

yond the position of minimum air gap length.

The parts being assembled as described and shown, they may be very closely drawn together by turning the cap 14, and securely locked by the set-screw 28.

The core 1 is provided with longitudinal slots 39 to prevent eddy currents.

The core 1 being in the position shown, 10 the winding 38 is energized by an alternation of alternating current or by a pulsation of direct current. The flux generated by the winding flows through the L-shaped field members 10 adjacent to the winding, and through the adjacent portion of the casting 9, and through a portion of the core. This flux flows across the gap between the left end of the core and the extensions 13 of the left hand field members 10. This pulls the core to the left and causes it to strike the shank 35 of the tool 34. The winding 38 now becomes de-energized and the winding 37 is energized by another alternation or pulsation of current, which 25 causes a flux to be generated to pull the core to the right and against the core-stop 24, whereupon the second cycle of operation begins causing the core to move to the left and to the right as before. These cycles 30 continue as long as current is fed alternately to the windings in the manner described.

When a tool is not disposed in the hammer, and the core occupies its extreme forward position against the tool bushing 31, 35 the rear end of the core will be forward of and out of the rear air gap or flux region, and the core cannot then be moved by the rear solenoid 6. If the hammer is held vertically while the tool is out, the core will assume its extreme forward or lowermost position and will not respond to the flux of the retrieving coil 6. This is an important and desirable feature since reciprocation of the core while the tool is not in position would impress severe stresses upon the tool socket and tend to shear the threads 5 of the barrel. Damage to the hammer structure is thus precluded, however, if the operating switch be inadvertently closed while the tool is not in operating position, since the solenoid 6 will not actuate the core.

By having the inner ends of the field members project into openings in the barrel close to the core 1, in its different positions, the shortest possible transverse air-gaps are provided. I prefer to make the windings with a central internal annulus fitting between the opposed ends of the arms 12 so that the flux density between the said opposed ends and through the core and the gaps at its ends is increased.

Certain features disclosed in this application, including, among others, the construction and disposition of the magnetic field members or laminations, and the co-

operative relation of a movable core therewith, are claimed broadly in my co-pending application for a reciprocating electric motor, Serial No. 697,053, filed March 5, 1924, a continuation of application Serial No. 70 527,037, filed Jan. 4, 1922; and certain other features disclosed herein, particularly the double solenoid field structure broadly, is claimed in my co-pending application Serial No. 541,517, filed March 6, 1922. 75

I claim—

1. In an electric tool, a non-magnetic barrel, a tool shank at one end of the barrel, a core-stop at the other end thereof, two axially aligned windings surrounding the barrel, magnetic field members arranged around the barrel and within the windings, the field members being interrupted to form short air-gaps within the length of each winding, and a magnetic core reciprocable 85 in the barrel and having its ends arranged to be drawn into the air-gaps alternately by alternate energization of the windings.

2. In an electric tool, a non-magnetic barrel, a tool-shank at one end of the barrel, a core-stop at the other end thereof, two axially aligned windings surrounding the barrel, magnetic field members arranged around the barrel and within the windings, the field members being interrupted to form short 90 air-gaps within the length of each winding, and a magnetic core reciprocable in the barrel and having its ends arranged to be drawn into the air-gaps alternately by alternate energization of the windings, the magnetic members extending through the barrel-wall 95 at the ends of the air-gaps.

3. In an electric tool, a non-magnetic barrel, a tool-shank at one end of the barrel, a core-stop at the other end thereof, two axially aligned windings surrounding the barrel, magnetic field members arranged around the barrel and within the windings, the field members being interrupted to form air-gaps 105 within the length of each winding, and a magnetic core reciprocable in the barrel and having its ends arranged to be drawn into the air-gaps alternately by alternate energization of the windings, the magnetic members extending through the barrel-wall 110 at the ends of the air-gaps and the windings having each an internal annulus in the adjacent air-gap.

4. In an electric tool, a non-magnetic barrel, a tool-shank projecting into one end of the barrel, and a core-stop projecting into the other end thereof, two axially aligned windings surrounding the barrel, radially-arranged field members, having radial arms at the ends of the windings and other arms lying between the windings and the barrel, the ends of the second arms for each winding being spaced apart within the length of the winding, means for completing the magnetic circuits between the ends of the radial 125

arms, and a magnetic core reciprocable in the barrel between the tool-shank and the core-stop.

5. In an electric tool, a non-magnetic barrel, a tool-shank projecting into one end of the barrel, and a core-stop projecting into the other end thereof, two axially alined windings surrounding the barrel, radially-arranged field members, the members for each winding being in separate pairs, each having a radial arm at one end of the winding and a scond arm parallel with the barrel and lying between the latter and the winding, there being an air-gap between the ends of each pair of second arms, means completing the magnetic circuits at the ends of the radial arms, and a magnetic core reciprocable in the barrel between the tool-shank and the core-stop and having such a length as to have its ends magnetically drawn alternate-ly into the said air-gaps.

6. In an electric tool, a non-magnetic barrel, a tool-shank projecting into one end of the barrel, and a core-stop projecting into the other end thereof, two axially alined windings surrounding the barrel, means pro-viding magnetic circuits for the windings having air-gaps between the ends of the windings and wholly within the latter, and a magnetic core having its ends arranged to be drawn into air-gaps of the respective magnetic circuits from each end of its stroke.

7. In an electric tool, a non-magnetic barrel, a magnetic core reciprocable therein, a reciprocable core-stop in one end of the barrel, two axially-alined electro-magnets surrounding the barrel, laminated magnetic circuit members associated with each electro-magnet and disposed radially around the barrel, a casing surrounding the magnets and fitting tightly over the laminated mem-bers to complete the magnetic circuits, a nose-piece closing one end of the casing, a tool-bushing extending through the nose piece and into the barrel, and clamping the nose-piece to the barrel, a tool-shank in the bushing and projecting into the barrel and into the path of the core, a closure for the remaining end of the casing, and means ad-justably connected to the barrel for forcing the closures tightly against the ends of the casing and uniting the described parts into a rigid unit.

8. In an electric tool, a non-magnetic barrel, a magnetic core reciprocable therein, a reciprocable core-stop in one end of the barrel, two axially-alined electro-magnets surrounding the barrel, laminated magnetic circuit members therefor radially disposed around the barrel a casing surrounding the magnets and serving to complete the mag-netic circuit between the laminated mem-bers, a nose-piece closing one end of the cas-ing, a tool-bushing extending through the nose-piece and into the barrel, and clamping

the nose-piece to the barrel, a tool-shank in the bushing and projecting into the barrel and into the path of the core, a closure for the remaining end of the casing, and a cap screwing on the barrel and having a flange 70 working on the outer face of the second clo-sure to clamp the described parts into a rigid unit.

9. In an electric tool, a non-magnetic barrel, a magnetic core reciprocable therein, a reciprocable core-stop in one end of the barrel, two axially-alined electro-magnets sur-rounding the barrel, magnetic circuit mem-bers radially disposed around the barrel and serving to hold the magnets in place, a cas-ing surrounding the magnets and tightly fitting the magnetic members to complete magnetic circuits therebetween, a nose-piece closing one end of the casing, a tool-bushing extending through the nose-piece and into the barrel, and clamping the nose-piece to the barrel, a tool-shank in the bushing and projecting into the barrel and into the path of the core, a closure for the remaining end of the casing, a cap screwing on the barrel 90 and having a flange working on the outer face of the second closure to clamp the de-scribed parts into a rigid unit, and a spring to urge the core-stop toward the core and held under tension by the cap.

10. In an electric tool, the combination with a winding, of an inner shell built up of laminations to constitute a portion of the magnetic circuit for the winding and an outer shell serving as a casing for the tool 100 and as a portion of the magnetic circuit for the winding.

11. In an electric hammer, the combina-tion with a movable core member and an ac-tuating coil therefor, of a plurality of mem-bers constituting the internal magnetic cir-cuit conductor and an enclosing tube consti-tuting the external magnetic circuit con-ductor, said core having such characteristics and being so slotted as to provide paths of 105 relatively high resistance to electric cur-rents and relatively low reluctance to mag-netic flux.

12. An electric tool of the reciprocating motor type comprising a barrel provided 115 with an enlarged flange-like portion at each end constituting a shoulder on the barrel, one portion being externally threaded and the other end of the barrel being internally threaded, magnetic field members seated on 120 the barrel and snugly held in position against said shoulders by tenons fitting into the barrel, solenoids associated with said magnetic field members, a core responsive thereto, a casing fitting over the field mem-bers and enclosing the solenoids, a nose piece fitting over one end of the barrel against the field members, a tool socket for clamping the nose piece to the barrel, a bumper in the other end of the barrel, a handle piece fit- 125

ting over the same end of the barrel to cover the solenoid, and a cap secured to the handle end of the barrel to retain the bumper and the handle piece in position, the handle and nose pieces cooperating to hold the casing in position therebetween.

13. An electric tool of the reciprocating motor type comprising a barrel, a core movable therein, two solenoids disposed around 10 the barrel, magnetic field members comprising limiting portions for holding the sole- noids in position and locking portions fitting into the barrel, said members being radially disposed around the barrel, a casing fitting 15 over the limiting portions of the magnetic field members to enclose the solenoids and to serve as a magnetic conductor between the field members, means fitting over the ends of the barrel to enclose the ends of the sole- 20 noids, and means for locking said means in position and also to clamp the casing between said means to hold the several elements in a compact unit.

14. An electric tool of the reciprocating 25 motor type comprising a barrel or guide, a core member freely movable therein between predetermined limits, two solenoids axially alined around the barrel, magnetic field members for the respective solenoids 30 to concentrate the magnetic flux of the respective solenoids at predetermined regions of the path of travel of the core, and a casing of magnetizable material enclosing said coils and their field members and substantially closing the magnetic circuit of each 35 of said coils.

15. An electric tool comprising a reciprocating magnetizable core, a field winding, a plurality of groups of laminations spaced 40 circumferentially of the axis of movement of the core, and a casing of magnetic material enclosing said winding and groups of laminations and forming with said laminations a relatively fixed field structure with 45 respect to which said core is movable.

16. An electric tool comprising a reciprocating magnetizable core, a plurality of field windings disposed in different positions along the path of movement of said core, a plurality of circumferentially spaced groups of outwardly extending laminæ in the magnetic circuit of each of said windings, an air gap for each winding between the ends of groups of laminations approaching each 55 other longitudinally of the movement of said core, and an enclosing casing of magnetic material substantially closing the magnetic circuit between the outer portions of the groups of laminae.

60 17. An electric tool comprising a reciprocating magnetizable core, a plurality of field windings, and a plurality of circumferentially spaced groups of outwardly extending laminæ in the magnetic circuit of each of said windings, the adjacent groups of lam-

inæ for the different windings being separate from each other.

18. An electric tool comprising a reciprocating magnetizable core, a plurality of field windings, and a plurality of circumferentially spaced groups of outwardly extending laminæ in the magnetic circuit of each of said windings, the adjacent laminæ of the different windings being spaced from each other longitudinally of the movement of 75 said core.

19. An electric tool comprising a reciprocating magnetizable core, a plurality of field windings, a plurality of circumferentially spaced groups of outwardly extending lam- 80 inæ in the magnetic circuit of each of said windings, the adjacent groups of laminae for the different windings being separate from each other, and an enclosing casing of magnetic material substantially closing 85 the magnetic circuit of each of said windings.

20. A percussive tool of the reciprocating electric motor type comprising front and rear solenoids, a magnetizable core struc- 90 ture actuated by said solenoids, laminated field members for concentrating the magnetic fluxes produced by each solenoid in an air gap within the length of the solenoid, a yielding back-stop adjacent the air gap 95 of the rear solenoid, a tool bushing adjacent the front end of the motor, and a tool shank extending through said bushing and terminating adjacent the air gap of the front solenoid, the length of said core structure, 100 the length of the air gaps and the distance between the air gaps being such that the core structure is not actuated by the rear solenoid when said tool shank is removed and said core structure engages said bush- 105 ing.

21. An electric tool comprising a tool shank and a core stop adjacent opposite ends thereof, a plurality of field windings, magnetizable field members for each winding 110 spaced from each other longitudinally and approaching each other longitudinally to form an air gap, and a magnetizable reciprocating core engaging said tool shank and core stop and movable past the positions in 115 which it reduces said air gaps to minimum length.

22. An electric tool comprising a reciprocating magnetizable core, a plurality of groups of circumferentially spaced and out- 120 wardly extending laminæ disposed along the path of said core, a field winding positioned between adjacent groups of laminæ, and a casing of magnetizable material engaging the radial extensions of said laminæ which project beyond the outer periphery of said winding.

23. An electric tool comprising a reciprocating magnetizable core, a plurality of groups of circumferentially spaced and out- 125

wardly extending laminæ disposed along the path of said core, a plurality of axially aligned windings, each positioned between adjacent groups of laminæ, and a casing of magnetizable material enclosing said windings and engaging the radial extensions of

the outwardly extending laminæ which project beyond the outer periphery of the windings.

In testimony whereof I hereunto affix my signature this 22nd day of July, 1922.

CARL S. WEYANDT.
